PROCESS AND APPARATUS FOR CONVERT-
ING HYDROCARBON OILSJohn Wyckliffe Throckmorton, New York, N. Y.,
assignor to Gyro Process Company, Detroit,
Mich., a corporation of Michigan

Application September 2, 1933, Serial No. 687,986

13 Claims. (Cl. 196—60)

This invention relates to improvements in converting relatively heavy hydrocarbon oils into lighter hydrocarbon oils having the characteristics of motor fuel.

5 The novelty in the process lies principally in charging a relatively heavy oil to a primary heater and there raising it to a distillation temperature, after which the vaporizable and unvaporizable constituents are separated by 10 evaporation. The vaporized constituents are cracked in the vapor phase and immediately thereafter are quenched below active vapor phase cracking temperature by being intimately mixed with a relatively cooler oil. The liquid constituents are passed to a heater maintained under 15 pressure where they are subjected to a viscosity breaking reaction which reduces the percentage of heavy fractions and increases the vaporizable or lighter fractions therein. The quenched 20 cracked products mixed with those discharged from the viscosity breaker are flashed at reduced pressure in a flash tower, after which the vaporized portion is subjected to fractionation and condensation and the liquid bottom is diverted 25 as a fuel oil from the system.

Further improvement lies in the arresting or quenching of the cracked vapors discharged from the cracking stage by mixing them with a clean distillate withdrawn from the fractionating 30 stage and substantially completely vaporizable at the temperature and pressure conditions existing in the flash tower.

The process differs from conventional methods in that the percentage of vaporizable products in the substantially tar free bottoms accumulated in the evaporator is increased in the viscosity breaking stage. Also the temperature of the vaporizable products separated in the evaporator and returned to the vapor phase 35 cracking stage is controlled by introducing a portion of the clean recycle stock utilized as quench oil in the evaporator stage.

The single figure is a diagrammatic elevation of one form of apparatus in which my process 40 may be operated.

In operation, relatively heavy oil, such as 45 topped crude, is introduced through pipe 1, and is charged by means of a pump 2, through the line 3, which is connected into the fractionating 50 column 4. In the fractionating column, or tower, the charging stock is mixed with the reflux condensate which mixture is drawn off from the bottom of the tower 4 through pipe 5, and is charged by means of pump 6 through a line 7 55 into a distillation or primary coil 8, positioned

in the compartment 9 of a double furnace. This coil may be arranged in a bank of tubes in the convection and radiant sections of the furnace in order to obtain the most efficient heating of the oil, though I prefer to use only convection heat as shown in the drawing.

Heat is supplied to the furnace by means of burners 10 or by any other suitable means. In the coil 8 the charging stock is raised to temperatures of from 700° to 900° F., preferably an optimum temperature of 850° F. is maintained at the outlet from the furnace. The oil thus heated in primary coil 8 in the furnace 9 is discharged through a transfer pipe 11 controlled by a valve 12 and is discharged into an evaporator 13. In 15 the evaporator the vaporizable are separated from the unvaporizable products, the former passing out through the vapor line 13, and the latter being drawn off through a pipe 14 connected in the bottom of the evaporator. The 20 vapors passing out through the line 13 are directed through a vapor phase cracking or secondary coil 15, positioned in the furnace compartment 16. The vapors are heated to temperatures 25 from 950 to 1300° F., normal operating temperatures being approximately 1100 to 1200° F. The cracked products are discharged from the cracking furnace, passing through the pipe 17 into an arrester 18 where the temperature is reduced 30 by bringing the cracked vapors in intimate contact with a cooler oil supplied to the arrester through pipe 19. The cracking furnace is heated by burners diagrammatically shown by 20.

The oil used as a quenching medium, that is, for reducing the temperature of the cracked 35 products, is a clean tar free distillate withdrawn from the fractionating tower through pipe 21, passed thence through a cooler 22, and is collected in a working tank 23 from which it is 40 withdrawn through pipe 24 and forced by means of a pump 25, through the line 19 into the arrester 18.

The substantially tar free liquid oil accumulated 45 in the bottom of evaporator 13 is withdrawn through the line 14 and charged, by means of a pump 26 through line 27 into a viscosity breaker or tertiary heating coil 28 positioned in compartment 9 of the furnace. This coil may comprise radiant heat and convection heat section, in order to provide for efficient heating. This relatively heavy oil is subjected to the temperatures of the order of 700 to 900° F. in the viscosity 50 breaking coil 28, after which it is discharged through the transfer pipe 29 regulated by means of a valve 30. This valve may be used to hold 55

back pressure on the coil 28 when desired. The transfer pipe 29 connects to the discharge line 31 which directs the quenched cracked products from the arrester to a flash tower 32 wherein reduced pressures are maintained, or the transfer pipe 29 may be connected directly with the flash tower. Relative lower pressures are maintained in the flash tower than in the viscosity breaking coil and in the vapor cracking coil so that 10 substantially complete vaporization of the quench oil is effected. In the flash tower, I effect another separation of the vaporizable and unvaporizable products, the former passing overhead through a vapor line 33, which is connected 15 to fractionating tower 4 below the line 3, through which the charge is introduced into the tower, the charging stock thus acting as a refluxing medium to the vapors. The liquid bottoms or fuel oil accumulated in the flash tower and containing 20 the tar formed by the vapor phase cracking is withdrawn through the pipe 34 and is, discharged by means of a pump 35 through pipe 36 into a cooler 37, from which the residue passes 25 through line 38 controlled by valve 39 to storage, not shown.

It will be observed that I may introduce a portion of the clean distillate quenching stock through line 60, controlled by valve 61, into the evaporator, thus controlling in a measure, the 30 temperature, volume and composition of the vapors which pass through line 13 to the vapor phase cracking step.

Vapors passing from the flash tower into the fractionating column 4 rise and in their passage 35 therethrough are subjected to the refluxing action of a plurality of pools of oil maintained upon bubble trays diagrammatically shown by dotted lines in the tower. The material still in vapor form at the top of the tower passes off through the vapor line 40 to a vapor condenser 41 and is collected as liquid distillate in the separator 42 which is equipped with a gas relief line 43 regulated by a valve 44, and the distillate drawoff line 45 controlled by a valve 46. A portion of the 40 distillate may be returned through the pipe 47 by the agency of the pump 48 to the top of the 45 tower as refluxing medium.

In the event it is desired to charge the oil directly to the heating coil 8 instead of subjecting 50 it to predistillation in the tower, a cross over line 49 is provided between the pipes 3 and 7. Valves 50 and 51 serve to control the flow through the cross over and direct the charge directly to the distillation heater 8 instead of to the tower 55 4. By the arrangement, a part of the charge may go direct to the heater and a part to the tower if desired.

As suggested, the invention lies principally in 60 reducing the percentage of relatively heavy or high boiling point fractions in the bottoms drawn off from the evaporator by subjecting the same to viscosity breaking reaction in the heating coil 15 and thereafter flashing at reduced pressure a mixture of the reheated bottoms and the 65 quenched cracked bottoms in a flash tower maintained under reduced pressure to separate the heavy tar and gums from the vaporizable constituents.

Invention resides also in the use solely of a clean 70 tar free distillate as a quench oil for the cracked vapors and the utilization of a portion of this clean distillate as a material to be introduced into the evaporator for controlling the temperature of the vapors charged to the vapor phase 75 cracking stage.

An illustrative run typical of the operation is as follows: a topped crude from an oil of the Mid Continent area of the United States, having a gravity of approximately 27.0° A. P. I. was charged to the fractionating tower and there mixed with a cycle stock. The mixture was heated in the furnace chamber 9 to a distillation temperature of approximately 750° F. The vaporizable and unvaporizable constituents were separated in the evaporator 13. The vapors were then 10 cracked in the furnace 16 at temperatures in the neighborhood of 1100° F. and immediately thereafter cooled by being mixed with a cooler quench oil returned from the fractionating tower down to about 650° F. The bottoms from the evaporator were heated in the viscosity breaking coil 28 in the furnace chamber 9 to 850° F. and under a pressure of 200 pounds or above. On being discharged from the viscosity breaker the pressure in the oil was reduced and a combination of the 20 quenched cracked products and the heated oil from the viscosity breaking coil was flashed under a reduced pressure of from 10 to 80 pounds in the tower 32. The vapors released were fractionated and the motor fuel fractions condensed. The 25 liquid bottom from the flash tower was diverted from the system as marketable fuel oil meeting bunker C. specifications (according to U. S. Bureau of Mines Technical Paper No. 323B). The motor fuel distillate had an end boiling point of 30 420° F. and an antiknock rating of 85 (C. F. R. research method).

Having thus described my invention, what I claim is:

1. The process of converting hydrocarbon oils 35 comprising the steps of charging a mixture of relatively heavy oil and light oil to a primary heating zone and there heating it to a distillation temperature, separating by evaporation the vaporizable and unvaporizable materials in an 40 evaporating zone, cracking the vapors in a secondary heating or cracking zone, and immediately thereafter reducing the temperature of the cracked vapors to below active vapor phase cracking temperature by quenching them with a cooler 45 hydrocarbon, heating in an elongated confined stream the unvaporized oil recovered from the initial separating zone to temperatures sufficiently high to increase the percentage of vaporizable material therein in a tertiary heating 50 or viscosity breaking zone, combining the quenched products discharged from the secondary vapor cracking stage and the bottoms discharged from the tertiary heating stage and flashing the mixture at reduced pressure in a flash zone, diverting the unvaporized oil from the system, subjecting the vapors separated in the flash zone to fractionation in a fractionating zone and condensing the vapors.

2. A process such as that described in claim 1, 60 wherein pressure is reduced between the tertiary heating zone and the flash zone.

3. A process such as that described in claim 1, 65 wherein pressures up to 150 pounds are maintained in the evaporating zone, pressures up to 50 pounds on the flash zone, pressures up to 75 pounds on the secondary heating or vapor cracking zone, and pressures up to 400 pounds on the tertiary or viscosity breaking zone.

4. A process such as that described in claim 1, 70 including the step of blending the heavy and light oils of the charge in the fractionating zone, withdrawing a selected clean distillate from said fractionating stage and utilizing it to quench the 75

- cracked products from the secondary vapor cracking stage and combining a portion thereof with the oil in the evaporating stage to control the temperature of the vapors charged to the 5 vapor cracking stage, as well as the quality or percentage of cycle stock in the bottoms returned to the tertiary or viscosity breaking stage.
5. An apparatus for cracking hydrocarbon oils comprising primary, secondary, and tertiary 10 heaters, an evaporator connected to the primary heater and by vapor and liquid lines to the secondary and tertiary heaters respectively, a flash tower connected to the secondary and tertiary heaters, a fractionating tower and condensing means serially connected to the flash tower, a return line from the fractionating tower to the discharge from the secondary heater and to the evaporator and a residue drawoff line from the flash tower.
6. A process of converting hydrocarbon oils into hydrocarbons of lower molecular weight including the steps of passing hydrocarbon oil in an elongated confined stream and heating it to distillation temperature in a primary heating zone, 20 flashing the oil into vapors and unvaporized oil in an evaporating zone, withdrawing the vapors from the evaporating zone and passing them in an elongated confined stream and heating them to active vapor phase cracking temperatures in a conversion zone, withdrawing the cracked vapors 25 from the conversion zone and immediately reducing their temperature to below an active vapor phase cracking temperature by contacting them with a sufficient quantity of relatively cooler hydrocarbon oil in a reaction arresting zone, withdrawing the unvaporized oil from the evaporating zone, passing it in an elongated confined stream and heating it to temperatures sufficiently high to produce an appreciable amount of lower boiling 30 hydrocarbons in a viscosity-breaking zone, withdrawing the heated oil from the viscosity breaking zone, withdrawing the oil and vapors from the reaction arresting zone, introducing the oil from the viscosity breaking zone and the oil 35 and vapors from the reaction arresting zone into a flashing zone maintained at a reduced pressure, and there separating the material thereinto introduced into oil vapors and unvaporized oil, withdrawing the unvaporized oil from the process, 40 fractionating the oil vapors in a fractionating zone and recovering hydrocarbons of lower molecular weight from the fractionating zone.
7. A process as in claim 6 wherein a selected side stream distillate is withdrawn from the fractionating zone and used as the oil introduced into the reaction-arresting zone.
8. A process as in claim 6 where a selected side stream distillate is withdrawn from the fractionating zone and a portion introduced into the reaction arresting zone to reduce the temperature of the cracked vapors and another portion thereof introduced into the evaporating zone to control the evaporation therein. 5
9. A process as in claim 6 wherein the oil charged to the primary heating zone comprises reflux condensate withdrawn from the fractionating zone and fresh oil to be converted is charged to the fractionating zone. 10
10. An apparatus for cracking hydrocarbon oils comprising in combination a first heating means, a viscosity breaking heating means and 15 a cracking heating means, an evaporator tower, means for passing oil from said first heating means to said evaporator tower, means for passing vapors from said evaporator tower to said cracking heating means, means for passing oil 20 from said evaporator tower to said viscosity breaking heating means, a reaction-arresting chamber, means for passing vapors from said cracking heating means directly to said reaction arresting chamber, a flashing chamber, means for passing oil from the reaction arresting chamber into the flashing chamber, means for introducing oil from said viscosity breaking heating means into said flashing chamber along 25 with oil passed thereto from said reaction arresting chamber, means for withdrawing from the process oil from said flashing chamber, a fractionating tower, means for introducing vapors from said flashing chamber into said fractionating tower, means for introducing reflux 30 condensate from said fractionating tower into the reaction arresting chamber, a condenser, means for passing vapors from the fractionating tower to said condenser. 35
11. An apparatus as in claim 10 including means for introducing hydrocarbon oil into the fractionating tower and means for passing reflux condensate from the fractionating tower to said first heating means. 40
12. An apparatus as in claim 10 including means for introducing reflux condensate from the fractionating tower into the evaporator tower. 45
13. An apparatus as in claim 10 wherein the evaporator tower, the cracking heating means, and the flash tower are maintained at progressively decreasing pressures in the order named. 50
